J. S. SHURMAN.
RERAILER FOR STREET CARS.
APPLICATION FILED OCT. 28, 1921.

1,404,661.

Patented Jan. 24, 1922.

UNITED STATES PATENT OFFICE.

JOSEPH S. SHURMAN, OF UNITY STATION, PENNSYLVANIA.

RERAILER FOR STREET CARS.

1,404,661.

Specification of Letters Patent. Patented Jan. 24, 1922.

Application filed October 28, 1921. Serial No. 511,087.

To all whom it may concern:

Be it known that I, JOSEPH S. SHURMAN, a citizen of the United States, residing at Unity Station, in the county of Allegheny and State of Pennsylvania, have invented certain new and useful Improvements in Rerailers for Street Cars, of which the following is a specification.

This invention relates to a rerailing device for use in reseating derailed cars upon the track rails.

The invention has for an object to provide a simple and efficient device for the above purpose.

For further comprehension of the invention, and of the objects and advantages thereof, reference will be had to the following description and accompanying drawings, and to the appended claims in which the various novel features of the invention are more particularly set forth.

Fig. 1 of the drawings is a plan view of a rerailing device constructed according to the invention, showing it applied to a rail-road track, the form of rerailing device shown in this figure being intended more particularly for use where the rails are set in a paved roadbed.

Fig. 2 is a detail transverse section on the line 2—2 of Fig. 1.

Fig. 3 is a side view thereof.

Fig. 4 is a detail transverse section on the line 4—4 of Fig. 1.

Fig. 5 is a similar view to Fig. 1, but showing a form of the device suitable for use on a gravel or other unpaved roadbed.

Fig. 6 is a detail transverse section on the line 6—6 of Fig. 5.

In the drawings the reference numeral 10 indicates a pair of track rails of ordinary construction, and 11 the sleepers or ties.

As shown in Figs. 1 to 4 of the drawings my improved rerailing device comprises a pair of blocks 15, 15' adapted to rest beside the rails 10 and having integral runway members 16, 16' extending from opposite ends thereof which are of wedge shape as seen in side view to provide inclined surfaces leading upwardly to the tops of the blocks. These runway members 16, 16', as shown in plan view, each have one edge extending along the adjacent rail in parallelism thereto, while the opposite edge inclines as shown to cause the runways to widen from the block toward their opposed ends.

Extending along the said upwardly in-

clined side edges of the runways 16, 16', are upwardly projecting ribs 17, 17' while the runways have second ribs 18, 18' extending therewith adjacent the ribs 17, 17'. Formed 60 in the tops of the blocks 15, 15' are pairs of intersecting slots 20, 20' which cross the blocks from end to end, the slots 20 which are in the block 15 located between the two track rails, being in substantial alignment 65 with the inclined spaces between the ribs 17 and 18, one end of each slot communicating with said space and the other end being closely adjacent the rail 10. The slots 21 register with the space between the ribs 18 70 and the rail, and cross over the latter.

Formed on the blocks 15, 15' on the opposite side of the rail to the runway members are rail engaging members 22 of triangular shape and of hollow construction, these members being adapted to hold the rerailing elements against displacement from the rails. These members 22 preferably each have an opening 23 formed therein for convenience in grasping when the device is to be removed 80 from the rail. The sides of the blocks opposite the members 22 are preferably constructed in the form of pointed elements 24.

In the modification of the invention shown in Figs. 5 and 6 of the drawings blocks 25, 25' are provided which are in the main similar to the blocks, 15 and 15' and have like runway members 26, 26' formed on opposite ends thereof. In these blocks the members 23 are omitted and for securing the blocks 90 in place on the rails a bar 27 having a hook 28 on one end adapted to engage the base-flange of the rail, is passed through a suitable slot in each block, and under the rail, a screw 29 being inserted in the proper one 95 of a number of apertures 30 in the bar 28 to hold the parts against displacement. To prevent loss of the screw 29 the same may be attached to the block by a chain 31.

In the operation of the device the ribs 18, 18' form track elements on which the wheels run up the runways 16, 16', the slots 20, 20' accommodating the flanges of the wheels as the latter pass over the blocks and serve to properly guide the wheels upon the rails 10. 105

While I have shown and described preferred forms of my improved rerailing device, suitable for use on paved and unpaved roadbeds, it is to be understood that I do not limit myself in any way to the precise 110 construction shown and the right is reserved to all such changes and modifications as come

within the spirit and scope of the invention as defined in the appended claims.

Having thus described my invention what I claim as new and desire to protect by 5 Letters Patent of the United States is as follows:

1. In combination with a track rail, a rerailing device comprising a pair of blocks having integral inclined runway elements 10 extending from opposite ends thereof, the top face of said blocks having pairs of intersecting slots extending from end to end thereof, a pair of spaced ribs extending along the side of each runway member re- 15 moved from the rail, the slots in one block communicating with the space between said ribs, and in the other block communicating with the space between the rib and the rail.

2. In combination with a track rail, a re- 20 railing device comprising a pair of blocks having integral inclined runway elements extending from opposite ends thereof, the top face of said blocks having pairs of intersecting slots extending from end to end 25 thereof, a pair of spaced ribs extending along the side of each runway member removed from the rail, the slots in one block communicating with the space between said ribs, and in the other block communicating 30 with the space between the rib and the rail, the slots in the first block extending to a point adjacent the outer side of the rail, and the slots in the other block extending across the rail.

3. In combination with a track rail, a re- 35 railing device comprising a pair of blocks having integral inclined runway elements extending from opposite ends thereof, the top face of said blocks having pairs of intersecting slots extending from end to end 40 thereof, a pair of spaced ribs extending along the side of each runway member removed from the rail, the slots in one block communicating with the space between said ribs, and in the other block communicating 45 with the space between the rib and the rail, and means for securing said block to the rail.

4. In combination with a track rail, a re- 50 railing device comprising a pair of blocks having integral inclined runway elements 55 extending from opposite ends thereof, the top face of said blocks having pairs of intersecting slots extending from end to end thereof, a pair of spaced ribs extending along the side of each runway member removed from the rail, the slots in one block communicating with the space between said ribs, and in the other block communicating with the space between the rib and the rail, 60 and means for securing said block to the rail, said means including a hollow integral element adapted to engage the opposite side of the rail, and having an aperture 65 therein, for the purpose specified.

In testimony whereof I have affixed my signature.

JOSEPH S. SHURMAN.
